UNITED STATES PATENT OFFICE

2,658,509

HERNIAL TRUSS

George Ajdukovich, St. Louis, Mo.

Application June 2, 1950, Serial No. 165,775

2 Claims. (Cl. 128—101)

1

This invention pertains to a truss such as is used for the treatment of hernia or rupture.

One of the objects of this invention is to provide an improved truss structure which will tend to keep a pair of truss pads in place in their original adjustment to the body of the wearer.

Another object is to provide such a device which is so formed as to apply retaining pressure through a pair of pads erected as nearly as possible in opposition to the direction in which the hernia under treatment tends to move out.

Another object is to provide a truss structure in which a pair of truss pads is mounted so that each of the pads conforms to the body of the wearer in spite of the wearer's movements.

Another object is to provide a truss structure which will be cheap to manufacture and rugged and durable in service.

Other objects will appear to those skilled in the art in the light of the following description and the accompanying drawing.

In accordance with an illustrative embodiment of this invention, a truss is provided having an elastic belt on which is mounted a pair of truss pads. Lying along the elastic belt beneath the truss pads is a relatively inelastic but flexible strip which allows limited movement of the truss pads with respect to one another, but which fixes the relative positions along the belt of the two pads. When appropriate mounting means for the pads, such as screws, are employed, the pads may easily be adjusted along the belt relative to one another. The flexible inelastic strip may be mounted by the same means by which the truss pads are mounted on the belt. The mounting means for one of the pads may be used to secure a buckle member.

In the drawing,

Figure 1 is a perspective view of one embodiment of this invention in use.

Figure 2 is a view in front elevation of one embodiment of this invention.

Figure 3 is a plan view of the embodiment of this invention shown in Figure 2.

Figure 4 is a view in rear elevation of the device shown in Figure 2.

Figure 5 is a perspective view of a device not in use.

Figure 6 is a sectional view taken along the line 6—6 of Figure 5.

Figure 7 is a perspective view showing the concave side of a truss pad for use with this invention.

Referring now to the illustrative embodiment of this invention shown in the drawings, and

2

particularly to Figure 5, the complete truss 1 comprises an elastic belt 2, a pair of truss pads 3 and 4 and a flexible but relatively inelastic connecting member 5. A buckle member 6 is attached by mounting means 7, which in the embodiment shown in Figure 5 are screws, taking into supporting columns 8 projecting from the concave side 9 of the truss pad 4. Truss pad 3 is also provided with supporting columns 8 and mounting means 7. Attached to the end of elastic belt 2 opposite the end 12 of belt 2 to which the buckle member 6 is attached, is a complementary buckle member 10 provided with teeth 11 for adjusting the effective length of belt 2.

Connecting member 5 may be made of a limp material such as cloth, leather, inelastic plastic or the like. Elastic belt 2 may be made with inserts of rubber or in any other suitable fashion to allow it to stretch along its length.

Flexible connecting member 5 may be unsecured to elastic belt 2 except by mounting means 7. In that case, when mounting means 7 are removable, the entire assembly of pads and connecting means may easily be adjusted with respect to the belt. Flexible connecting member 5 may be stitched at either end to belt 2 in which event, when releasable mounting means are employed, the pads are still adjustable with respect to one another. If, on the other hand, rivets or other permanent mounting means are employed, the pads are adjustable neither with respect to one another nor with the belt.

In assembling this device, elastic belt 2 may be laid flat and connecting member 5 laid thereon. Truss pads 3 and 4 are then positioned along connecting member 5, and mounting means 7 are inserted through elastic belt 2 and connecting member 5 and into supporting columns 8. If it is desired to incorporate a buckle member 6 into this assembly, that member is positioned before

mounting means 7 are inserted to mount pad 4, and mounting means 7 are inserted through suitable holes in buckle members 6 when truss pad 4 is mounted. The assembly shown in Figures 2 through 6 has the advantage that not only is buckle member 6 attached in a single operation with the attachment of truss pad 4 but the legs of buckle member 6 provide reinforcing for mounting means 7 at that point, while connecting

member 5 serves to reinforce mounting means 7 from the strain of securing buckle member 6. Furthermore, the buckle so located is in a convenient position.

While in describing the assembly of this device the belt was described as being laid flat and the

connecting member laid thereon, it will be seen from the drawings, and particularly Figure 3, that the effective length of connecting member 5 may be made shorter than the span of the belt 2 between the truss pads. In so assembling the device, the connecting member 5 may be held straight while the elastic belt is bowed outwardly. When the length of connecting member 5 between the truss pads is less than the span of the elastic belt 2, elastic belt 2, having a greater radius than connecting member 5 will draw in against the connecting member 5 when in use. This means that when such a shortened connecting member is used, the pads will tend to assume an angle depending on the relative lengths of the sections of connecting member and elastic belt between the mounting means. Thus a method of adjusting the angle between the truss faces when the belt is in use is provided.

A truss is thus provided in which the truss pads are held against longitudinal movement with respect to the belt and one another so that the pads remain positioned at the proper points, but are allowed to move inwardly toward the body and outwardly away from the body, relative to one another with movements of the wearer's body. This permits a relatively constant pressure to be exerted by each pad and provides a comfortable, simple, and cheaply constructed device. Furthermore, by varying the length of the inelastic member relative to the span of the elastic belt which it covers, the angle at which the pads tend to bear upon the area to be supported may readily be adjusted. Thus, not only is the device comfortable, simple and cheap, but readily adjustable, both as to the angle at which the pads are to act and as to the relative positions of the pads longitudinally of the belt.

Numerous variations, such as in the number and position of supporting columns, in the shape of the pads, in the construction of buckle members, and in the materials used, within the scope of the specification and appended claims will be apparent to those skilled in the art.

Having thus described my invention, what is claimed and desired to be secured by Letters Patent is:

- 10 1. A truss comprising an elastic belt, a pair of truss pads mounted along said belt, and a flexible but inelastic member connecting said pads in fixed, spaced relationship along said belt, said connecting member being positioned between the said truss pads and the said elastic belt and having a span less than the span of the elastic belt
- 15 2. A truss comprising an elastic belt, a pair of truss pads mounted along said belt, and a limp and inelastic member connecting said pads in fixed, spaced relationship along said belt, said connecting member being positioned between said truss pads and the said elastic belt.

GEORGE AJDUKOVICH.
